CARD CASE

Filed Sept. 21, 1928

Fig. 4.

INVENTOR:
WILL J. ECKER JR.

BY *Arthur C. Eckert*
ATTORNEY.

UNITED STATES PATENT OFFICE

WILL J. ECKER, JR., OF ST. LOUIS, MISSOURI

CARD CASE

Application filed September 21, 1928. Serial No. 307,512.

The object of my invention is to make a card case for storage of personal or business cards. A further object is to make a card case, that is small and compact and may be 5 easily carried in the pocket of the owner. One that is light in weight and that will prevent the cards from becoming soiled or torn, and will permit the easy removal of the cards one at a time. A still further object of my 10 device is to make a case in which the cards will be so positioned that each card will slightly overlap the succeeding lower card while in position.

With these and other objectives in view my 15 invention has relation to certain novel features of construction and arrangement of parts as will be hereinafter more fully described, claimed and illustrated in the drawing in which

20 Fig. 1 is a plan view of my device with the lid in its open position.

Fig. 2 is a longitudinal sectional elevation on the line 2—2 of Fig. 3.

25 Fig. 3 is an end elevation of my device with the lid in a partially raised position.

Fig. 4 is an end elevation of my device with the lid in its closed position.

30 Numeral 5 indicates cards that are to be stored in my device. The card case consists of the bottom 6, the side walls 7, and the end walls 8 and 9.

35 Numeral 10 indicates the lid secured to the end wall 8 by means of the hinge 11. The box thus far described is of conventional form. The bottom, sides and ends, being made integral or stamped are secured together in a conventional manner.

40 Numeral 12 designates a lip secured to the free end of the lid 10 at right angles with the plane of the lid. In the end wall 9 is formed the finger depression 13 of the same shape and size as the lip 12. When the lid is in its closed position the lip 12 is in the same plane as the end wall 9. By means of this lip 45 12, the lid may be easily grasped for the purpose of opening. On the sides of the lid 10 in spaced relationship therewith are formed the flanges 14 at right angles to the plane of the lid 10; near the front of the lid 50 behind the lip 12 is formed the flange 15.

The flanges 14 and the flange 15 are connected together at right angles. These flanges are of such shape and dimension that when the lid is in its closed position, they extend slightly into the body of the case and help form a 55 dust proof juncture between the lid and the walls of the case.

Numeral 16 designates a leaf spring which is centrally secured to the bottom 6 near its rear end, that is to say, approximately beneath the hinge 15. The cards 5 when positioned in the case are supported on the leaf 60 spring 16.

Numeral 17 designates a false rear wall, which is secured to the bottom 6 by means of the flange 18 by soldering or other conventional means. The false rear wall 17 is bent forwardly as best shown in Fig. 2, and has the flange 19 formed at its upper end, extending forwardly. The false rear wall 17 is of 65 such height that the flange 19 will be parallel to the lid 10 when the lid 10 is in a closed position and will be immediately beneath it. The cards 5 are positioned, so that the upper card is placed immediately under the flange 70 75 19. The flange 19 may be made of the configuration best shown in Figure 1.

Numeral 20 designates a spring post, which is secured to the bottom 6 by means of the flange 21 by soldering or any conventional 80 means. The upper end of the spring post 20 is bent rearwardly as best shown in Fig. 3, and has a small knob formed on its free end. The spring post 20 is sufficiently resilient to resume its normal position shown in Fig. 2 85 after being bent forwardly. Spring post 20 is in its normal position when the cards 5 are positioned as shown in Fig. 2. The spring post 20 is positioned near one of the side walls 7 and a short distance from the end wall 9. 90 When the cards 5 are inserted into the case they are first placed on the leaf spring 16, which is slightly compressed to enable the upper card to be placed immediately beneath flange 19. The cards are then pressed rearwardly until their ends are in contact with the false rear wall 17. The spring post 20, is then pressed slightly forwardly and the cards lowered. The spring post is then released until it assumes the position shown in 95 100

Figure 2. The cards are now held firmly in the case and each card extends forwardly slightly beyond each succeeding lower card. When it is desired to remove one card after the lid 10 is raised, the upper card is easily grasped at the corner opposite from the spring post 20, and by virtue of the resilience of the card and the spring post 20, is easily raised above the spring post 20. The cards may then be pulled forward from beneath the flange 19.

What I claim and mean to secure by Letters Patent is:

1. A card case comprising a bottom, rear and end walls, a false rear wall secured in said case and inclining forwardly with a flange at its upper forward end, a spring post secured in said case near the forward end of the case for selectively holding the cards in the case.
2. A card case comprising a bottom and side and end walls, a false rear wall inclining forwardly and secured to the bottom of said case, a resilient spring post secured adjacent one forward corner of said case to the bottom of said case, said spring post having a flange at its free end, said false rear wall and said spring post coacting to hold the cards to be stored in said case securely with each card extending forward slightly more than the succeeding lower card in order to facilitate the removal of individual cards.

In testimony whereof I affix my signature.

WILL J. ECKER, JR.
